UNITED STATES PATENT OFFICE.

AMBROSE RYDER, OF NEW YORK, N. Y.

UMBRELLA.

1,328,901.

Specification of Letters Patent. Patented Jan. 27, 1920.

Application filed October 10, 1917, Serial No. 195,686. Renewed May 27, 1919. Serial No. 300,182.

To all whom it may concern:

Be it known that I, AMBROSE RYDER, a citizen of the United States, residing at New York city, in the county of New York and State of New York, have invented certain new and useful Improvements in Umbrellas, of which the following is a specification.

This invention relates to umbrellas. The term umbrella is to be understood as inclusive of parasols and sunshades.

The ordinary umbrella, with the stick in the middle, gives the user the benefit of hardly more than one-half of the protective covering. The object of this invention is, therefore, to provide an umbrella in which the user has the benefit of substantially all of the protective covering, and it consists of the improvements which I will now describe, referring to the annexed drawings in which,—

Figure 1 is a vertical, central section of the umbrella in the raised position,—the sectioning of the covering in this and the following figures being omitted for clearness.

Fig. 2 is a similar view showing another and analogous form of construction.

Fig. 3 is a similar view showing another and analogous form of construction.

Fig. 4 is an enlarged detail of the stick portions, showing my joint mechanism in the closed position.

Fig. 5 is a view similar to Fig. 4, showing the parts in the open position.

By "open position" is meant the position of the parts when the umbrella is raised and the handle adjusted to the carrying position.

Referring first to Fig. 1, the ribs are shown at 1, 1, and the trusses for the ribs at 3, 3. The ribs are pivoted to a crown-piece 2 in the usual manner, and this crown-piece 2 is mounted on a stud 5, which occupies the position of the stick in an ordinary umbrella. Sliding on this stud 5 is a sleeve 4', and to a pivot-flange on this sleeve 4' the trusses 3 are pivoted. The covering is indicated at 15.

The stick or handle 7 has a pivot end 16 by which it is pivoted to the crownpiece 2. This may be done by a lug extension on the crownpiece 2, as shown, or by having the end 16 forked to engage over the crownpiece, or it may occupy one of the ordinary rib-slots in the crownpiece in like manner as a rib is pivoted.

To a lug 17 on the handle 7 is pivoted a truss 18, and the other end of the truss 18 is pivoted to a lug 19 on the sleeve 4'. A latch 16' holds the sleeve 4' in the open position.

The pivotal positioning of the several trusses to the ribs and to the sleeve 4' and the pivotal positioning of the truss 18 to the stick 7 and to said sleeve are such that, when opened, the parts occupy the position substantially as shown, and when closed, the parts will lie compactly together—the stick 7 lying parallel with and adjacent to the stud 5.

It will now be seen that, by this construction, the stick is brought to one side of the umbrella and away from the main axis, so that the user has the benefit of substantially the entire covering. The angle which the stick 7 forms with the stud 5 when in the raised position may be any desired angle up to the limit of contact with the covering. For example, Fig. 3 shows the stick at the maximum angle with the stud, and as replacing one of the ribs. The truss 18 is shown here as one of the trusses 3, 3. Fig. 3 also shows the special joint in the stick as explained hereinafter.

Referring next to Figs. 2, 4 and 5, the ribs 1, 1, are pivoted to the crownpiece 2 in the usual manner, and the trusses 3, 3, are pivoted to the ribs 1, 1, and to a sleeve 4. But the sleeve 4 does not slide on the stick of the umbrella. At its upper end it is slightly bell-shaped, and when the umbrella is in the open position, engages over a stud 5 on the under side of the crownpiece 2. The lower end of the sleeve 4 is provided with a knob by which it may be grasped to open and close the umbrella. Over the sleeve 4 is a pivot-flange 4" to which are pivoted the inner ends of the trusses 3, 3. This flange is so positioned that, in opening the umbrella, the trusses 3, 3, will be on a dead center soon after the sleeve 4 engages the stud 5, so that when the sleeve goes to final position on said stud, the thrust of the trusses will be upward and will hold said sleeve firmly over the stud 5, and thus hold the umbrella in the open position.

In place of one of the series of ribs as shown in Figs. 2 and 3, is the stick 7" with handle 7', which is pivoted at its upper end to the crownpiece 2 in substantially the same manner as the ribs, and to the part 7" the

covering 15 is secured by any desirable means, as to an eye *e* on said part.

The handle portion 7' of the stick is connected to the part 7" in the following manner: A bar or lever 9 is rigidly secured to the part 7" and at its upper end is pivoted to the part 7", as at 10. Pivoted to a lug on the bar 9 is a second bar 11, which at its upper end is pivoted to a sleeve 12 which 10 slides on the part 7".

To hold the two parts 7" and 7' in axial alignment when in the closed position, a sliding ferrule 8 on the part 7' engages over the part 7", forming a ferrule joint. When 15 the handle portion 7' is released from the closed position of the handle, shown in Figs. 2 and 4, by slipping the ferrule 8 downwardly to the position shown in Figs. 3 and 5, the handle 7' may be swung to the 20 carrying position shown in Fig. 3. This brings the handle 7' to a vertical position and away from the edge of the covering 15, so that drip from the covering will not run down the handle.

25 To hold the parts just described in the open position, the stick 7" has a latch 13, normally spring-forced outwardly, and a stop 14, positioned to limit the upward movement of the sleeve 12 when the handle 30 is brought to the carrying position.

The operation for the construction shown in Fig. 2 is as follows: Assuming the umbrella to be closed, it is partially opened by merely holding the handle and pushing 35 up on the knob-end of the sleeve 4 until the same reaches, say, the position shown in Fig. 3. At this point the spring action of the ribs and the tension of the covering puts thrust upon the sleeve 4 through the trusses 40 3, 3, and more pressure is applied, much the same as with an ordinary umbrella. With this further pressure, the sleeve 4 and the trusses 3, 3, pass the dead center, and then the thrust of the trusses tends to force the 45 sleeve 4 upwardly, and the sleeve then goes home over the stud 5, and the thrust will continue to hold the umbrella in the open position. The ferrule 8 is then slipped down to release the handle 7' from the stick 50 7", and permits the lever 9 to push the bar 11 upwardly and with it the sleeve 12. By bringing the handle to the vertical position shown in Fig. 3, the stop 14 will limit the movement of the sleeve 12 and the latch 13 55 will hold the handle in the raised position. The operation of closing is substantially a reversal of the operation described.

It is now evident that, when in the open position described, the handle portion 7' is 60 in a vertical position well to one side of the center of the umbrella, but free from the drip edge of the covering.

In Figs. 1 and 3 the covering is spread open by pushing up on the knob-end of 65 sleeve 4' until the sleeve engages over the

stud 5. More pressure is applied until the covering is fully opened and the latch 16' snaps to place against the knob-end of the sleeve.

It will now be seen that Fig. 1 shows the 70 umbrella with the stick at an angle to the customary central position of umbrella handles; Fig. 3 shows a similar construction with the stick at the maximum angle with this customary central position and replacing one of the ribs; Fig. 2 shows a modification of the sleeve and stud; and Figs. 2, 3, 75 4, and 5 show a modification of the stick.

This construction gives the user the benefit of practically all the covering and the 80 improvement is effected without wide departure from standard construction and standard parts. This construction also presents special advantages in connection with sunshades and parasols and is particularly 85 advantageous in a crowd or against a wind.

Having thus described my invention, I claim:

1. In an umbrella, the combination of a 90 crownpiece, ribs and a stick pivoted to said crownpiece, with a sleeve pivotally secured to the inner ends of the trusses, ribs pivoted to said trusses and to said crownpiece, a stud rigid with said crownpiece, adapted to engage said sleeve, and the pivotal positioning of said trusses to said sleeve and on said ribs being such that said sleeve is held against said crownpiece when the umbrella is in the open position by the thrust 95 of said trusses. 100

2. In combination with the parts set forth in claim 1, said stick occupying the position of a rib and adapted to being secured to the covering, covering, a handle and means between said handle and said stick 105 positioned to act as a rib to adjust said handle to a vertical position when the umbrella is open.

3. In combination with the parts set forth in claim 1, covering for the umbrella, a handle, a ferrule coupling for holding said handle in line with said stick in the closed position, a bar pivoted to said stick and rigidly secured to said handle, a bar pivotally connecting said first-mentioned bar to 110 a sleeve adapted to slide on said stick, a sleeve on said stick and a stop and latch on said stick to hold said sleeve in the open position. 115

4. In an umbrella of the type described 120 and in combination with ribs, trusses, a crown piece and covering, means coöperating with the ribs and trusses to hold the covering in open position, a stick pivoted to said crown piece and adapted to act as 125 a rib and a handle for said stick, and adjustable means between said stick and said handle, whereby the two are held axially in line in closed position and whereby said handle is moved to an angular position with 130

respect to the stick when the umbrella is opened and said handle adjusted.

5. In an umbrella, the combination of ribs, trusses, a crown piece and covering, means coöperating with the ribs and trusses to hold the covering in open position, and a straight stick pivoted to said crown piece and acting as a rib for the covering, one of said trusses connecting the stick and said 10 means and being of such limited length that when the covering is open the axis of the crown piece forms a relatively acute angle with the stick, whereby the covering is held in tilted position with respect to the 15 stick.

6. In an umbrella, the combination of

ribs, trusses, a crown piece and covering, means coöperating with the ribs and trusses to hold the covering in open position, and a straight stick pivoted to said crown piece 20 and acting as a rib for the covering, one of said trusses connecting the stick and said means and being of such limited length that when the covering is open the axis of the crown piece forms a relatively acute angle 25 with the stick, whereby the covering is held in tilted position with respect to the stick, and the length of the ribs and covering on the side opposite the stick being greater than on the side toward the stick.

AMBROSE RYDER.
